FREE ARM SEWING MACHINE

Marcel Fresard, Petit-Lancy, Geneva, Switzerland, assignor to Mefina S.A., Fribourg, Switzerland, a corporation of Switzerland

Filed Nov. 21, 1963, Ser. No. 77,535

Claims priority, application Switzerland May 28, 1963

Term of patent 14 years

(Cl. D70—1)

FIG. 1

FIG. 2

Des. 201,406

FIG. 3

FIG. 1 is a front perspective view of a sewing machine showing my new design;

FIG. 2 is another front perspective view thereof as it appears turned at a slightly different angle;

FIG. 3 is a top plan view thereof;

FIG. 4 is a rear perspective view of the sewing machine shown in FIGS. 1 and 2; and

FIG. 5 is an end view taken from the right-hand side of the sewing machine shown in FIGS. 1 and 2.

I claim:

The ornamental design for a free arm sewing machine, substantially as shown.
